UNITED STATES PATENT OFFICE.

VERNON J. HARWARD AND WALTER P. BUDD, OF DURHAM, NORTH CAROLINA.

ROOFING CLIP.

Application filed July 12, 1923. Serial No. 651,183.

To all whom it may concern.:

Be it known that we, VERNON J. HARWARD and WALTER P. BUDD, citizens of the United States, residing at Durham, in the County of Durham and State of North Carolina, have invented certain new and useful Improvements in Roofing Clips, of which the following is a specification.

This invention relates to improvements in roofing clips.

The primary object of this invention is the provision of a roofing clip which is particularly well adapted for use in connection with the laying of individual shingles on a roofing structure, embodying means whereby the shingles may be uniformly laid and spaced and held effectively in place upon the roof against liability of easy disarrangement therefrom.

A further object of this invention is the provision of a roofing clip which may be used in connection with the laying of individual shingles, embodying novel means whereby adjacent shingles may be accurately spaced and secured together upon a roof structure.

A further object of this invention is the provision of a roofing clip of the above mentioned character, which embodies improvements set forth in our copending application, serial No. 651,184 filed July 12, 1923.

Other objects and advantages of this invention will be apparent during the course of the following detailed description.

In the accompanying drawing, forming a part of this specification, and wherein similar reference characters designate corresponding parts throughout the several views:

Figure 1 is a fragmentary plan view of a roof, showing a part of the same covered with individual shingles uniformly exposed and spaced by means of the improved roofing clip.

Figure 2 is a fragmentary longitudinal cross sectional view taken through the roofing structure, showing the improved co-operation of the clips with the shingles of the roofing structure.

Figure 3 is a fragmentary cross sectional view, taken through upper and lower shingles adjacent a connection of an improved clip therewith.

Figure 4 is a perspective view of the preferred form of improved roofing clip.

Figure 5 is a modified form of the improved roofing clip.

In the drawing, wherein for the purpose of illustration are shown preferred and modified forms of this invention, the letter A may generally designate the preferred form of improved roofing clip, which may be used in connection with the laying of individual shingles B upon a roof F. In lieu of the preferred form of clip A, a modified form of clip H may be used.

Referring briefly to the method of laying individual shingles upon a roof, a lower tier of shingles 10 are laid longitudinally along the eaves of the roof, said tier of shingles being but one third the length of the ordinary shingle. A second tier of shingles 11 are laid in superposed relation upon this tier 10, said tier of shingles 11 being two-thirds of the length of an ordinary shingle. The upper tier of shingles 12 are placed on top of the tier 11, at the eave of the roof. In laying roofing of these individual shingles B, the shingles must be spaced from each other to allow for expansion and contraction of the shingles incident to variations in temperature. This space between shingles of standard size is ordinarily one-half inch, but in the actual laying of the shingles upon a roof, workmen are prone to be negligent, and very frequently the shingles are joined together, having no space between them, with the consequence that they will buckle. The superposed tiers of shingles rearwardly of the eaves tier 12, as illustrated in Figure 1, are placed so that the shingles are exposed for a short distance to the weather, which in the case of a standard size shingle of 8 inches by 12 $\frac{3}{4}$ inches, is usually a four inch exposure. It is extremely difficult to lay the superposed tiers of shingles accurately and in line to present a finished roof having a proper uniform appearance.

Referring to the improved clip A, the same has been provided to facilitate laying of individual shingles B, and to insure that the same will be properly spaced from each other and properly exposed for the required distance. This clip A is preferably constructed of sheet metal, providing a T-shaped body portion 15, which includes a shank 16 at the upper end of which the laterally extending attaching wings 17 and 18 are provided. At the top marginal edge 20 of the clip attaching portion 15, and on the

opposite side of the wings 17 and 18 from that from which the shank 16 extends, a spacing tab or projection 21 extends, preferably of the same width as the width of the shank portion 16; said tab or flange 21 extending in a plane at right angles to the plane of the attaching portion 15, and being of a depth equal to the depth of a shingle B. At its free end and, of course, remote from 10 the wings 17 and 18, the shank portion 16 of the attaching body 15 is preferably arcuated, as at 22, above the shank 16, and has a retaining tab 23 bent upwardly over the shank 16, which at its free end 25 is directed 15 downwardly toward the plane of the body 16, and substantially at an acute angle thereto. The attaching wings 17 and 18 are preferably provided with openings 28 and 29 respectively therethrough, which are 20 adapted to receive nails or like securing elements. The openings 28 and 29 continue in an upwardly extending reduced slot portion 30 toward the marginal edge 20 of the body portion 15; said openings and the slots in 25 said wings in effect extending longitudinally in parallel relation with the shank 15, the same being provided with the novel retaining tab 23 for purposes, which are set forth in our copending application, Serial No. 30 651,184, filed July 12, 1923.

Referring to the application of the improved clip A, upon the roof F, the lowermost clips over the eaves of the roof are placed upon the tier of roofing 11, and the 35 tier 12 of the shingles B are then properly placed over the eave of the roof, and in such relation as to provide spaces 35 therebetween. The retaining tabs 23 of the lowermost row of clips A, receive the thickness 40 of the shingles B comprising the tier 12. The next transverse row of cleats A are placed upwardly of the shingles B of the lowermost tier 12, so that the front portion 22 of said clips are placed about four inches 45 above the lowermost row of clips. These clips are placed with the tab or flange 21 resting within the slot 35 between adjacent shingles B, to close the slot beneath the superposed shingles. The attaching wings 17 50 and 18 are placed over and secured to adjacent shingles B. The tiers of shingles B above the eave tier 12 are then placed across the roof, and the clips A attached as they are placed to place adjacent shingles B for 55 the proper spacing 35. It will be noted that incident to the provision of the tabs 23, the proper exposure of all shingles B is effected to present a uniform appearance. The space 60 35 between all of the shingles is the same, as this spacing is determined by the width of the spacing flange 21. After the clip A has been placed upon a shingle, and the superposed shingle is received in the retaining tab 23 thereof, the roofer, by hitting the 65 retaining tab 23 will cause the same to en-

gage flat over the top of the superposed shingle, and kick the front 22 forwardly slightly in accordance with the invention set forth in our copending application above mentioned.

From the foregoing description of this invention, it is apparent that the provision of the clip A will enable a roofer to apply the individual shingles B to a roof in a minimum of time, and to correctly and effectively position the same. No additional nailing of the individual shingles is required in the use of the clip A than is required for the present method of roofing. The clip A serves an additional and important function in 70 that the spacing flange 21 thereof effectively closes the slot or space between adjacent shingles, so that snow and ice and other foreign elements cannot be blown beneath the superposed shingles. The clips additionally make the shingles self aligning and facilitate the laying of the roof.

Referring to the modified form of clip H, the same is preferably formed of wire, and bent intermediate its ends to provide the 75 laterally extending looped wing portions 40 and 41 having the transversely elongated openings 42 therein. Parallel arm portions 43 and 44 extend from the loops 40 and 41 and at their free ends are upwardly turned, 80 as at 45 and 46 respectively, over the arms 43 and 44; the upturned ends 45 and 46 providing retaining portions which are 85 downwardly turned, as at 47, in acute angular relation with respect to the run of 90 the arms 43 and 44, and which in effect provides a structure which will perform the function defined in our copending application 95 above referred to.

Various changes in the shape, size and arrangement of parts may be made to the forms of clips herein shown and described, without departing from the spirit of the invention or the scope of the claims.

We claim:

1. As an article of manufacture, a roofing clip adapted to act as a spacer for the application of individual shingles to a roof, said clip being formed of sheet material and comprising an attaching portion adapted to 115 bridge space between side edges of adjacent shingles and extend transversely across adjacent side portions of the shingles, upper and lower tongues extending from the attaching portion intermediate the width 120 thereof, the upper tongue being bent to extend in a plane at right angles to the plane of the attaching portion and adapted to be disposed between the adjacent shingles and act as a spacer for the adjacent shingles, the 125 lower tongue extending from the attaching portion in the plane thereof and having its free end portion bent to provide an upwardly disposed portion for engaging the lower end of a shingle overlying the said 130

adjacent shingles and limiting downward movement of the last mentioned shingle.

2. As an article of manufacture, a roofing clip comprising a body portion having a depending spacing flange extending downwardly therefrom transversely thereof and of less width than the width of said body portion, said body portion having openings transversely formed therein outwardly of

10 the ends of said spacing portion.

3. As an article of manufacture, a roofing tab formed of sheet metal comprising a substantially T-shaped attaching portion which includes a shank and laterally extending

apertured wings at the top thereof, said attaching portion at the top marginal edge thereof having a spacing flange bent downwardly substantially at right angles to the normal plane of the attaching portion, said spacing flange being of less width than 20 the width between the marginal outer edges of said attaching wings, the shank portion of said attaching portion having at the lower end thereof an upturned and overly bent retaining tab.
